TENNIS BALL HOLDER

Fred J. Hatley, Maywood, Ill.

Application April 6, 1936, Serial No. 72,872

4 Claims. (Cl. 224—5)

This invention relates to tennis ball holders, and among other objects aims to provide a simple and effective means for relieving a tennis player of the necessity of holding spare tennis balls in the hand, and yet which will make it possible to secure another ball as conveniently and quickly as though it had been carried in the hand.

The nature of the invention may be readily understood by reference to one illustrative device embodying the same and shown in the accompanying drawing.

In said drawing:

Fig. 1 is a perspective view of a single holder secured to the belt of a player;

Fig. 2 is a side view of the holder; and

Fig. 3 is a rear elevation thereof.

Many tennis players find it difficult to serve or to play effectively while carrying spare tennis balls, and yet are obliged to do so because of the inconvenience which would otherwise ensue. The illustrative device may be carried on the person in such a way as not to interfere with the player's freedom of play; it is adapted to release or to receive a ball with a single movement of the hand; and can be easily disconnected from the clothing of the wearer when not in use.

As here shown, the device comprises a pair of resiliently mounted rings 10 and 11, in this case of spring wire, whose diameter is substantially less than that of the tennis ball they are intended to hold. At one point in the circumference of each of the rings they are mounted to a base 12 in such a way as resiliently to resist separation. In unstrained relationship, the rings are separated at one point by a distance A, which is great enough in relation to the diameter of the tennis ball for the rings to be spread apart by a tennis ball 13 when the latter is pushed between the rings (see dotted lines 13 in Fig. 2). When pushed completely into the holder, the rings close somewhat (to the positions indicated by the dotted lines at 14 and 15 in Fig. 2) and resiliently embrace the ball sufficiently firmly to prevent its accidental discharge from the holder. Nevertheless, the ball can be withdrawn easily by hand simply by grasping and pulling it away from the rings which thereupon resiliently separate to release the ball.

The holder is advantageously provided with some means by which it may conveniently be attached to and detached from the clothing of the wearer. In the present instance, such attaching means are represented by hook 16 adapted to fit over some portion of the wearer's cloth-

ing such as the belt 17. The holder or holders may be located in the positions which are most convenient to the particular player.

The holder may advantageously comprise a single strand of wire (such as spring brass wire of 16 to 18 gauge) bent to form the rings and the hook 16 integral therewith. The folding or bending of the wire to form the various elements may be considerably varied. One method of bending the wire is illustrated in Fig. 3. As there shown, a portion adjacent one end of the wire is bent into the lower loop 10, the extremity of such portion being indicated at 18, and a portion at the opposite end of the wire is bent to form the upper ring 11, the opposite extremity of the wire being indicated at 19 and in this case lying adjacent the extremity 18. The intermediate portion of the wire comprises the upwardly extending members 20 and the integral hook member 16 which is flared outwardly as indicated at 21 to provide a wider bearing surface. The wire extremities 18 and 19, together with the members 20 are preferably bound or anchored together by a binding member in the form of a strap or of a flat sleeve 22 which provides a firm anchor at one point for the respective rings 10 and 11 so as to give them the necessary anchorage for the resilient pressure which they are required to exert in holding a tennis ball. If desired, the binding action of the member 22 may be supplemented by solder 23 so as more firmly to anchor the several strands of the wire against relative displacement inside the member 22. The free end of the loop 16 is arranged so as to converge upon the base 12 thereby making it possible for the hook to grip the portion of the clothing where applied. The doubled parts of the wire strand adjacent the extremity 24 of the hook may advantageously be brought into parallel relationship as illustrated at 25 to make it possible to anchor the hook to a button 26 inside the belt. In applying and removing the holder the button head passes through the flared portion 21 of the hook. The extremity 24 is outwardly flared to facilitate application.

Being made practically wholly from inexpensive wire the device may be made at extremely low cost. It is so light in weight that as many as necessary may be worn by the player without consciousness of their presence.

Obviously the invention is not limited to the details of the illustrative device since these may be variously modified. Moreover it is not indispensable that all features of this invention be used conjointly since various features may be

used to advantage in different combinations and sub-combinations.

Having described my invention, I claim:

1. A tennis ball holder of the character described comprising in combination a strand of spring wire, said wire being bent adjacent each end into the form of a ring whose diameter is less than that of a tennis ball, said rings being relatively arranged with their planes in outwardly diverging relationship, the remaining portions of said wire being bent into parallel relationship at the point of closest convergence of said rings and extending from such point in a direction substantially transverse to the planes of said rings, means for binding said wire together adjacent said point of closest convergence of said rings to anchor said rings, a portion of the wire in parallel relationship being bent over to form a hook for attaching said holder to the clothing of the user.
2. A tennis ball holder of the character described comprising in combination a resilient strand of wire bent adjacent each end into a ring whose diameter is less than that of a tennis ball, the portions of the wire at the beginning and the end of each ring being bound together to anchor said rings to permit relative flexure, said rings diverging outwardly from the point of anchoring at such relative angle as to be sprung apart upon the insertion of a tennis ball, the remaining portions of the wire extending from the point of anchoring at an angle to the planes of said rings and being bent to form a hook for

the attachment of said holder to the clothing of the user.

3. A tennis ball holder of the character described comprising in combination a resilient strand of wire bent adjacent each end into a ring whose diameter is less than that of a tennis ball, the portions of the wire at the beginning and the end of each ring being bound together to anchor said rings to permit relative flexure, said rings diverging outwardly from the point of anchoring at such relative angle as to be sprung apart upon the insertion of a tennis ball, the remaining portions of the wire extending from the point of anchoring being doubled and being bent into hook form, the doubled portions forming the hook being spread apart to fit over a button in attaching the holder to the clothing of the user.

4. A tennis ball holder of the character described comprising in combination a single resilient strand of wire bent adjacent each end into a ring whose diameter is less than that of a tennis ball, said rings being arranged with their planes in diverging relationship, the portions of said wire intermediate that forming said rings being doubled and bent into hook form for attaching the holder to the clothing of the user, and means for binding together the strands of wire in parallel relationship and to provide an anchorage for permitting relative flexure of said rings upon the insertion and removal of a ball.

FRED J. HATLEY.
